Claims priority, application Great Britain, Feb. 17, 1966, Ser. No. 7,075/66

1 Claim. (Cl. 200—44)

ABSTRACT OF THE DISCLOSURE

This invention relates to ignition switches for road vehicles, comprising as shown in the accompanying drawings, a casing having a rotor rotatably mounted therein, cam means acting to locate the rotor at any one of a number of positions relative to the casing, a contact assembly arranged to complete circuits in certain positions of the rotor, and an additional switch having a fixed part carried by the casing and a movable part carried by the rotor.

This invention relates to ignition switches for use in road vehicles.

A switch according to the invention includes a casing, a rotor, cam means acting to locate the rotor at any one of a number of positions relative to the casing, a contact assembly arranged to complete circuits in certain positions of the rotor, and an additional switch having a fixed part carried by the casing and a movable part coupled to the rotor for movement therewith.

One example of the invention is illustrated in the accompanying drawings wherein FIGURE 1 is a sectional side view of an ignition switch, FIGURE 2 is a sectional view on the line 2—2 in FIGURE 1, FIGURE 3 is an end view of the switch viewed in the direction indicated by the arrow A in FIGURE 1, and FIGURE 4 is a fragmentary perspective of part of the switch, and FIGURE 5 is a fragmentary sectional view on the line 5—5 in FIGURE 1.

The ignition switch illustrated in the drawings is of the key operated type having four operative positions, an off position in which the key may be removed from the switch, a first position achieved by rotating the key in a clockwise direction, in which ignition and auxiliary circuits of a road vehicle are energised, a second position, achieved by rotating the key further in a clockwise direction, in which a starter motor circuit of the vehicle is also energised, and a third position, achieved by rotating the key in a counterclockwise direction from the off position, in which only the auxiliary circuit is energised.

Referring to the drawings there is provided a cylindrical casing 11 which is stepped to provide a shoulder 18, and is closed at its wider end by an annular contact board 14. A hole 15 in the contact board 14 is closed by a resilient cup shaped member 51 mounted in a synthetic resin material. The member 51 is formed with a pair of arcuate outwardly extending flanges 52 at its open end, which engage shoulders 15a formed in the inner face of the board 14 to prevent withdrawal of the member 51.

A pair of rivets 53, 54 extending through the base of the member 51 and secure a pair of terminal blades 55, 56 to the outer face thereof, the heads of the rivets 53, 54 forming contacts 53a, 54a within the member 51.

Rotatable within the narrower cylindrical part 12 of the casing 11 is the core (not shown) of a cylinder lock, the part 12 of the casing 11 constituting the barrel of the lock. Within the wider part 11a of the casing 11 is a rotor 16, rotatably supported at one end in the member

51 and secured at its other end to the core of the lock for rotation therewith.

The rotor 16 is moulded in a synthetic resin material and is formed with a head 17 of substantially elliptical configuration (FIGURE 2). The head 17 abuts against the shoulder 18 of the casing 11 and extending axially from the head 17 is a hollow substantially cylindrical shank 19, having a pair of diametrically opposite, longitudinally extending flats (not shown), the end of the shank 19 being rotatably supported in the member 51. The shank 19 is also formed with a pair of longitudinally extending diametrically opposite slots 22, in which are engaged the ends of an electrically conductive roller 57. A spring 58 housed within the shank 19, urges the roller 57 into contact with cam forms 59, 59a moulded on the inner wall of the member 51.

Surrounding the shank 19 is an annular contact plate 23 provided with projections 24, the hole in the plate 23 being shaped complementarily to the shank 19 so that the plate 23 rotates therewith.

Associated with the board 14 are four contacts 26, 27, 28, 29 each of which incorporates one or more terminal blades positioned externally of the plate 14 for connection to external circuits, and a contact portion on the interior of the plate, the contact portions extending into holes in an insulating plate 35 over which the projections 24 move.

The contact plate 23 is urged towards the contact board 14 by a spring 36, one free end 36a of which is engaged in a further longitudinal slot 22a in the shank 19, and the other free end 36b of which extends towards the inner wall of the casing 11.

The rotor 16 is provided with an axially extending bore 38 of non-circular cross section with which is engaged a complementarily shaped spigot which extends from the core of the cylinder lock. By virtue of this engagement the rotor 16 is rotatable with the core of the lock. In the head 17 is a radial bore 39 containing a ball 41 which is urged by a spring 42 into engagement with an arcuate cam track 43.

The cam track 43 comprises three angularly spaced depressions 44, 45, 46 and a ramp 47. When the switch is in its off position the ball 41 is engaged with the depression 45 of the cam track 43 and the projections 24 of the contact plate 23 engage with the insulating member 35. When the switch is in the off position the roller 57 is supported clear of the contacts 53a, 54a by the cam forms 59, 59a against which the roller 57 is urged by the spring 58.

If it is required to energise the auxiliary circuit of the vehicle an ignition key is inserted into the core of the lock and rotated in a counterclockwise direction. Since the core of the lock, the rotor 16, the contact plate 23 and the roller 57 are not rotatable relatively to one another, angular movement of the key results in angular movement of the plate 23 relatively to the board 14 and angular movement of the roller 57 relatively to the cam forms 59, 59a of the member 51. By rotating the key in a counterclockwise direction the plate 23 is moved to a position in which it bridges the input and auxiliary contacts and so completes the auxiliary circuit. The cam forms 59, 59a of the member 51 are such that the roller 57 is maintained in a position clear of the contacts 53a, 54a. When the plate 23 is in the position in which it completes the auxiliary circuit the ball 41 engages the depression 44 which prevents accidental rotation of the key and consequently the plate 23. By virtue of the engagement of the end 36a of the spring 36 with the slot 22 in the shank 19, the spring 36 is rotated with the shank 19.

To complete the ignition circuit of the vehicle the key is turned in a clockwise direction, the ball 41 engages the depression 46 and the plate 23 bridges the input, ignition and auxiliary contacts thereby completing the igni-

tion and auxiliary circuits. The ends 36b of the spring 36 now engages a lug 37 formed as part of the cam track 43. To energise the starter motor of the vehicle the key is rotated further in a clockwise direction which forces the ball 41 to ride up the ramp 47 and causes the contact plate 23 to bridge the input and starter contacts while maintaining the bridge between the input and ignition contacts. However, since the end 36b of the spring 36 is engaged with the lug 37, such further rotation of the key in a clockwise direction causes the spring to be twisted, so that if the key is now released the spring 36, now acting as a torsion spring, will return the switch to its first position in which the ball 41 engages the depression 46 and the ignition circuit is still completed but the starter motor circuit is broken.

The cam forms 59, 59a include a pair of diametrically opposite depressions in which the ends of the roller 57 locate when the ignition circuit is complete the roller 57 is urged by the spring 58 into the depressions. These depressions are sufficiently deep to ensure that the roller 57 bridges the contacts 53a, 54a so as to complete a circuit therethrough. Thus the switch completes two separate circuits and in effect acts as a double pole ignition switch.

The part 12 of the casing 11 is externally screw threaded to facilitate mounting of the switch on the dash board or bulkhead of the road vehicle.

Having thus described my invention what I claim as new and desire to secure by Letters Patent is:

An ignition switch comprising in combination a first

hollow casing, a rotor, means mounting the rotor for angular movement within said first casing, a contact board closing one end of said first casing, said contact board having a central hole formed therein, movable contacts carried by the rotor, co-operating detent means on said first casing and said rotor serving to define operative positions of the switch, said movable contacts engaging respective fixed contacts carried by said contact board in said operative positions, a second casing non-rotatably engaged in said hole in the contact board, a pair of fixed contacts carried by said second casing, a conductive roller carried by said rotor and located within said second casing, a cam form on the inner surface of said second casing, and means urging said roller into engagement with said cam form, said roller riding on said cam form as the rotor is moved angularly, and the shape of said cam form being such that said roller bridges the pair of fixed contacts carried by said second casing in one of the operative positions of the switch.
